BED OR SIMILAR ARTICLE OF FURNITURE

James A. Womack, Atlanta, Ga.

Application October 6, 1947, Serial No. 778,223

7 Claims. (Cl. 5—308)

1

This invention relates generally to the class of furniture and pertains particularly to improvements in beds or similar articles of furniture.

A principal object of the present invention is to provide in association with a bed or similar article of furniture, a drawer structure which is accessible from either side of the article of furniture and which is conveniently stored beneath the same.

Another object of the invention is to provide in a structure of the character stated, a storage unit in the form of a drawer or the like which is mounted to slide in underneath the article of furniture to be in an out-of-the-way position when not in actual use by which is meant when articles are not being placed in or removed from the drawer or storage compartment.

A still further object of the invention is to provide in combination with an article of furniture such as a bed or the like, where a base portion is maintained in spaced relation above a floor, a storage receptacle in the form of a drawer, mounted to slide in beneath the base of the bed or other article of furniture, and accessible from either of two sides thereof.

Still another object of the invention is to provide a structure of the above described character wherein such drawer or storage compartment is rotatably mounted for turning on a vertical axis, in addition to being mounted for sliding movement so that all sections of the drawer or compartment are readily accessible when the drawer or compartment is drawn out from beneath the base of the article of furniture, means being provided to automatically secure the drawer against free rotation when it is in position to slide transversely of the bed.

The invention will be best understood from a consideration of the following detailed description taken in connection with the accompanying drawings forming a part of the specification with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 is a view in perspective of a bed frame base showing the present invention applied thereto, with the drawer drawn out.

Figure 2 is a top plan of the same.

Figure 3 is a section taken substantially on line 3—3 of Figure 2.

2

Figure 4 is a section taken substantially on line 4—4 of Figure 2.

Figure 5 is a fragmentary detail section taken substantially on line 5—5 of Figure 2.

Figure 6 is a detail section corresponding to Figure 5, but showing a modified floor support.

Figure 7 is an exploded view in perspective of the hanger unit.

Figure 8 is a detailed perspective of a modified portion of the hanger unit.

Figure 9 is a sectional detail showing the action of the securing buttons between the plate and channel member.

Referring now more particularly to the drawings, the numeral 10 generally designates the bottom or base frame of an article of furniture such, for example, as a bed. Reference will hereinafter be made to this frame as a bed frame but it is to be understood that the invention is not necessarily limited to such use and accordingly the frame of any other article of furniture of similar construction such, for example, as a sofa or the like, is to be included under such definition.

The bed frame as shown comprises the spaced parallel side boards or rails 11 and the transverse end rails or boards 12 which are connected with and supported by legs 13 in the usual manner.

In accordance with the present invention the inner side of each side rail 11 of the frame has secured thereto to run lengthwise thereof, the supporting metal angle bar 14. This angle bar 14 in one form as, for example, where it is installed in the original bed frame structure, may be provided with the oblique flange 15 which would be engaged in a suitable slot 16 formed in the inner face of the side rail 11 so that the horizontal angle or web portion 17 of the angle bar will be flush with the bottom edge of the rail 11 to which it is attached.

Where the invention is to be installed in an old bed frame structure, a simple L-shaped angle bar 14a will be disposed against the inner side of each side rail 11a and secured in position by screws 18 or any suitable similar means. In this case also, as will be readily apparent, the horizontal flange or web of the angle, here designated 17a, will be positioned so that its under side is in the same plane as the bottom edge of the rail 11a to which it is attached.

In the application of the present invention, the usual spring supporting slats or bars which are used in a bed frame are eliminated and a solid floor or horizontal wall structure is positioned within the frame to rest upon the opposite angle bars or rails. Such floor is here generally design-

nated 19 and may be made up of solid boards of suitable thickness or of ply board of suitable weight or thickness as desired, the two sides of the floor resting on the horizontal flanges and there being provided at each end the transverse bars 20 and midway of the ends of the floor is a central transverse bar 21. As shown, the floor 19, is divided in the two sections *a* which are in spaced relation at the transverse center of the bed frame and the central bar 21 is suitably supported above the space between the adjacent edges of the floor sections *a* and couples the sections together.

In the transverse space between the sections *a* of the floor, which transverse space is designated 22, there is secured the metal track which is generally designated 23. This track is of channel form, having the relatively wide top wall 24 and the narrow vertical side walls 25, each of which joins an inturned track flange 26 at its lower edge which terminates in the low upturned lip 27.

As shown in Figure 4 and indicated at 28 the floor sections *a* are rabbeted at their lower or bottom corners to receive the horizontal flange 17 of the supporting angle bracket. This brings the bottom surface of the floor in the same horizontal plane as the under side of the supporting flange or web of the angle. It will also be readily apparent that the two ends of the channel track 23 are closed by the vertical portions of the angle brackets toward which they are directed.

The numeral 29 generally designates a drawer or storage compartment of relatively shallow form and open at its top. Such drawer comprises the opposite face panels 30 which are provided with hand pulls 31, and the connecting side walls 32 which are set in slightly from the ends of the face panels 30 as shown in Figure 2. The numeral 33 designates the bottom of the drawer and extending between the face panels 30 or what may be termed lengthwise of the drawer, is a relatively wide division wall 34. This division wall may be of solid construction but preferably it is made up of two plywood strips or panels 35 which are maintained in spaced parallel relation by the interposed longitudinally extending, top and bottom blockings 36 and 37. By providing the additional transverse walls 34a, the drawer may be divided into four separate compartments, if desired.

At the exact center of the drawer there is secured to the division wall 34, a hanger unit by means of which the drawer is suspended from the metal track 23. This hanger unit is generally designated 38, in Figures 3 and 4.

The hanger unit 38 comprises a plate 39 which carries at each end the two laterally extending trunnions 40 upon each of which are rotatably mounted the rollers 41. The two rollers at each side of the plate 39 rest upon a flange 26 so that the plate 39 is supported for movement transversely of the bed frame, lengthwise of the track 23.

At the intersection of the longitudinal and transverse center lines of the plate 39 there is formed the aperture 39' which is of polygonal form, here shown as square. This aperture 39' has fitted therein the squared part 42' of a pivot pin or bolt 42. This part 42' is at the inner end of the threaded portion 42'', which extends beyond the top of the plate 39 and receives the securing nut 42a.

Beneath the squared portion 42' of the bolt is a portion 42b which is also of polygonal outline

and materially larger than the portion 42'. This larger portion 42b may be square like the portion 42' or of any other form desired, other than round.

5 The total length of the portions 42' and 42b is less than the overall length of the bolt 42 between the threaded portion and the head of the bolt so that there is left at the lower end of the bolt the circular portion *c* which extends to the bolt head *d*.

10 Disposed below the roller carrying plate 39 and suspended from the bolt 42 as hereinafter described, is a hanger yoke which is generally designated 43 and which comprises a relatively long rectangular top plate portion 44 and a lower downwardly opening channel portion 45 of approximately the same width and length as the plate 44.

15 The top plate 44 of the hanger yoke has the upstanding longitudinal edge flanges 44a and at the center of this plate is an opening 44b of the same form and size as the larger polygonal portion 42b of the bolt. Encircling this opening 44b and extending upwardly from the top of the plate 25 44 is the guide collar in which the part 42b of the bolt slides, this guide collar being designated 44c.

20 The plate 44 is also provided on the longitudinal center line, with the downwardly projecting buttons 46 which are rounded upon their undersides and are pressed from the metal of the plate 44.

25 The channel member 45 extends longitudinally of and lies over the division wall 37 and includes the down-turned longitudinal edge flanges 45a which position against the outer sides of the division wall as shown and have formed therethrough the bolt openings 45b for the passage of securing bolts or pins 46.

30 At the intersection of the longitudinal and transverse lines of the plate 45 is an aperture 45c which receives the portion *c* of the suspension bolt 42. Thus the head *d* of the suspension bolt is located upon the underside of the central part 35 of the channel member 45 and between the head *d* and the underside of the central portion of the channel member 45 is interposed the annual ball bearing race plate 47 which, together with an overlying bearing plate 47a, encircles the part *c* of the bolt the plate 47 being suitably channelled to receive the bearing balls 48 which bear against the plate 47a and support it in contact with the under face of the central portion of the channel member as best illustrated in Figure 3.

35 Encircling the enlarged squared portion 42b of the suspension bolt and also the collar 44c, and compressed between the plate 39 and the plate 44, is the compression spring 49. This spring functions to maintain the two hanger members 44 and 45 pressed tightly together and the central portion of the member 45 is provided along its longitudinal center line with the sockets or depressions 46a in which frictionally engage the projections or buttons 46 of the plate 44. Thus 40 it will be seen that relative rotary movement between the parts 44 and 45 is resisted until sufficient force is applied to the drawer to cause the rounded undersides of the buttons 46 to ride out of the sockets 46a thereby compressing the spring 49.

45 As an alternative construction, in place of the downwardly directed buttons 46 and the depressions 46a in the parts 44 and 45, use may be made of a spring pressed latch of the type employed 50 for securing or holding cabinet doors, such latch,

generally designated 46b, being shown in Figure 9, secured to the central portion of the lower channel member here designated 49a. The construction and operation of a latch of the type here shown and designated 46b is well known in the building trade. Such latch comprises a cylinder e which houses a spring, not shown, and which presses upwardly and partway through the open end of the cylinder, a ball or knob f. As the device is installed in the channel member 49a, the knob f projects above the top of the central portion of such member and is designed to frictionally engage in the downwardly opening socket 46c which is formed in the plate 44d.

Adjacent to each of the four corners of the drawer, each side wall 32 has secured to the outer side thereof at each end, the metal caster 49. These casters are mounted upon suitable supporting brackets 50 so that the wheels thereof will contact the underside of the bottom wall or floor 19. Thus by this contact of the casters with the floor the drawer or storage compartment is maintained horizontal at all times and if it is necessary to revolve the drawer on the bearing support at the center thereof, the caster rollers move against the underside of the floor to facilitate such revolving.

It will be readily apparent from the foregoing that the drawer structure 29 may be pulled out from either side of the bed frame to expose half of the drawer. Thus two of the compartments, where the drawer is divided into four compartments as shown, will be available and if it is desired to reach the other compartments this can be easily accomplished by revolving the drawer on the bearing carried by the suspension unit pin 42. During such rotation of the drawer at least two of the casters will always be in contact with the underside of the floor, thus functioning in association with the central suspension means, to maintain the drawer steady at all times.

By substituting the solid bottom wall or floor 19 for the usual spring supporting slats and by suspending the drawer so that the top thereof comes into close proximity to the underside of such floor bottom, it will be seen that effective coverage is given to the drawer to prevent excessive dust entrance.

I claim:

1. The combination with an article of furniture having a leg supported base frame, of a track secured transversely of the lower side of the frame, a drawer unit positioned beneath the lower side of the frame, a hanger attached to said drawer at the center thereof and including supporting wheels engaging said track for facilitating movement of the drawer across the under side of the frame, means forming a part of the hanger facilitating the rotation of the drawer on a vertical axis, and cooperating means between the corners of the drawer and the under side of the frame for maintaining the drawer horizontal during transverse and rotary movement of the drawer relative to the frame.

2. In an article of furniture having a leg supported base frame, a horizontal floor wall in the frame, a track supported transversely of the floor wall, a drawer having an open top and positioned immediately beneath the floor wall, and a hanger unit secured to the drawer in the center thereof, the hanger unit including a wheel carrying mem-

ber engaging said track and movable lengthwise thereof to facilitate moving the drawer outwardly from beneath either side of the frame.

3. A structure of the character stated in claim 5 2, wherein said track is in the form of a downwardly opening channel member having two spaced inturned flanges, the said wheel carrying member of the hanger unit comprising a plate positioned within the channel and a pair of wheels at each of two opposite sides of the plate, each pair of wheels resting upon a track flange.

4. An article of the character stated in claim 2, 15 wherein said hanger unit includes a vertical pivot bolt forming the connection between the drawer and the wheel carrying member and on which the drawer is rotatable in a horizontal plane, and roller members carried by the drawer at the top thereof and adjacent to the corners and contacting the under side of the floor wall.

5. An article of the character stated in claim 2, 20 wherein said hanger unit also includes a suspension bolt connected to the wheel carrying member and about the axis of which the drawer turns in a horizontal plane, and yieldable frictional holding means for securing the drawer against free turning movement when the drawer is in position for movement lengthwise of the track.

6. In an article of furniture having a leg supported base frame, a horizontal floor wall in the frame, a track supported transversely of the frame, the floor wall comprising two sections having spaced edge opposed relation and said track being secured between said spaced edges, 35 said track comprising an inverted channel member having spaced inwardly directed flanges along its open side in the plane of the bottom surface of the floor wall, a drawer having an open top and positioned beneath and in close proximity to said bottom surface of the floor wall to be closed thereby, the drawer having a central division wall, a yoke member engaged over the top edge of said division wall, and a hanger unit comprising a plate within the track channel, wheels carried by the plate and bearing upon said flanges and a bolt pivotally coupling said plate with said yoke member.

7. An article of furniture as set forth in claim 6, 45 wherein said yoke member has a flat top portion, friction means restricting the turning of the drawer on the bolt, comprising a plate resting upon the flat top of said yoke member, the second mentioned plate and top of the yoke member having interengaging studs and sockets, means 55 securing the second mentioned plate against turning around the bolt but permitting its movement lengthwise thereof, and a spring surrounding the bolt and interposed between the two plates to press the second mentioned plate against the flat 60 top of said yoke member.
